UNITED STATES PATENT OFFICE.

JOE SADLIK, OF YOUNGSTOWN, PENNSYLVANIA.

COMBINATION-BED.

1,359,623.

Specification of Letters Patent. Patented Nov. 23, 1920.

Application filed May 1, 1920. Serial No. 378,064.

To all whom it may concern:

Be it known that I, JOE SADLIK, a citizen of Poland, residing at Youngstown, county of Westmoreland, and State of Pennsylvania, have invented certain new and useful Improvements in Combination-Beds, of which the following is a specification.

This invention relates to beds having more particular relation to a bed structure 10 with which is combined an invalid's table and preferably also one or more seats, the invention being intended more particularly for embodiment in hospital beds, or other beds used by invalids.

15 The invention has for objects to provide a novel arrangement and mounting for an invalid's table on the bed frame, and for adjustable seats which may be moved under the bed when not in use.

20 More specifically speaking the invention has for an object, to provide an arrangement in which one of the end boards of the bed frame may be made to constitute the table.

25 For further comprehension of the invention, and of the objects and advantages thereof, reference will be had to the following description and accompanying drawings, and to the appended claims in which 30 the various novel features of the invention are more particularly set forth.

Figure 1 of the drawings is a perspective view of a bed frame having the invention applied thereto.

35 Fig. 2 is a side elevation, partly in longitudinal section, thereof.

Fig. 3 is a similar view to Fig. 1 but showing the parts in a different position with the table and seats ready for use.

40 Fig. 4 is a transverse sectional view of the bed frame, this view being taken at the point indicated by the line 4-4 of Fig. 3.

As here shown the frame of the bed is of 45 wood and consists of the four corner posts 10 united about midway between top and bottom thereof by the side bars 11 and end bars 12. These posts 10 are vertically slotted on their inner faces from their upper ends down to the end bars 12 as at

50 13, these slots receiving therein the side edges of the head board 14 and foot board 15, thus detachably securing these boards in place.

Hinged to the sides of the foot board 15 55 as at 16 are a pair of short links 17 whose opposite ends are provided with pins 18 en-

gaging in longitudinal slots 19 in a pair of struts 20, these struts extending at their lower ends across the inner faces of the side bars and being freely mounted on a transverse shaft 21 supported at opposite ends in longitudinal slots 22 in the side bars. The ends of this shaft 21 project beyond the side bars and have gear pinions 23 fixed thereon, these pinions meshing with racks 60 24 fixed on the side bars 11 below the slots 22. It will be obvious that by rotating the shaft 21, the struts will be moved longitudinally of the bed.

These struts are maintained upright in 70 adjusted positions by means of headed pins 25 engaging in longitudinally spaced sockets 26 in the upper edges of the side bars 11 and slidably carried in lateral offsets 27 from the struts 20 which project across the 75 said top edges of the side bars. These pins have suitable finger pieces on their upper ends whereby they may be lifted and are normally pressed downward into engagement with the sockets 26 by springs such as 80 28 carried in the offsets 27. Upon the upper ends of the struts 20 are formed extensions 29 projecting longitudinally of the bed and grooved as at 30 at their outer ends these grooves being adapted to receive and support the links 17 when the table is in use.

When not in use as a table the panel 15 occupies the position between the slotted posts forming the foot board of the bed as shown in Fig. 1. To adjust for use as a 90 table the panel 15 and links 17 are raised, the pins 18 in the ends of the links, moving in the slots 19 in the struts 20. The panel is then swung away from the posts 10, the links 17 being turned over until they rest 95 in the grooves 30 and the panel is swung to horizontal position on said links as shown in Fig. 3 where it forms a table which may be adjusted longitudinally of the bed by rotating shaft 21 as above pointed out. 100

To support the movable seats forming a part of my improved bed frame, a cross bar 35 extends between the side bars 11 and has hinged thereto, to swing in a horizontal plane, a pair of rigid arms 36 having seat 105 elements 37 on their outer ends. These arms as shown in Figs. 2 and 3 extend under blocks 37' rigid on the underside of the cross bar and are supported by a headed bolt 38 fixed to the cross bar. To hold the 110 arm in its inner or outer adjusted position a ball 39 carried in a suitable recess in the

block is pressed by a spring 40 against the face of the arm 36, this arm having shallow recesses such as 41 with which said ball engages.

5 Having thus described my invention what I claim as new and desire to protect by Letters Patent, of the United States is as follows—

- 10 1. In a bed, a detachable end board forming part of the bed frame, and means for adjusting said end board to and supporting said end board in a position forming a table, said means including a pair of links connected at one end to said end board, a pair of posts having vertical slots with which the opposite ends of said links connect, and means upon said posts for supporting said links in a horizontal position.
- 15 2. In a bed, a frame having a pair of corner posts formed with vertically grooved inner faces, and a pair of longitudinally slotted side bars, a panel slideable in the grooves in said posts, a pair of links connected at one end to said panel and having pins at their opposite ends, a shaft supported at opposite ends in the slotted portions of the said side bars, a pair of posts mounted upon said shaft adjacent the respective side bars, said posts having vertical slots into
- 20 30 which the pins on the opposite ends of said links project, projections from the upper ends of said posts extending longitudinally of the bed and forming supports for holding said links in a horizontal position.
- 25 35 3. In a bed, a frame having a pair of corner posts formed with vertically grooved inner faces, and a pair of longitudinally slotted side bars, a panel slideable in the grooves in said posts, a pair of links connected at one end to said panel and having

pins at their opposite ends, a shaft supported at opposite ends in the slotted positions of the said side bars, a pair of posts mounted upon said shaft adjacent the respective side bars, said posts having vertical slots 45 into which the pins on the opposite ends of said links project, projections from the upper ends of said posts extending longitudinally of the bed and forming supports 50 for holding said links in a horizontal position, lateral offsets upon said posts projecting across the upper edges of said side bars, and spring pressed pins in said offsets adapted to engage in sockets in said side bars.

4. In a bed, a frame having a pair of corner posts formed with vertically grooved inner faces, and a pair of longitudinally slotted side bars, a panel slideable in the grooves in said posts, a pair of links connected at one end to said panel and having 55 pins at their opposite ends, a shaft supported at opposite ends in the slotted positions of the said side bars, a pair of posts mounted upon said shaft adjacent the respective side bars, said posts having vertical slots 60 into which the pins on the opposite ends of said links project, projections from the upper ends of said posts extending longitudinally of the bed and forming supports 65 for holding said links in a horizontal position, lateral offsets upon said posts projecting across the upper edges of said side bars, and spring pressed pins in said offsets adapted to engage in sockets in said side bars, and 70 rack and pinion means for moving said 75 shaft, and with it the said posts and panel, longitudinally of the bed.

In testimony whereof I have affixed my signature.

JOE SADLIK.
